DESIGN FOR A WEIGHING SCALE

John R. Morgan, Oak Park, Ill., assignor to
Sears, Roebuck and Co., Chicago, Ill., a corpo-
ration of New York

Application April 29, 1937, Serial No. 69,061

Term of patent 7 years

To all whom it may concern:

Be it known that I, John R. Morgan, a citizen of
the Republic of Guatemala, residing at Oak
Park, in the county of Cook and State of Illinois,
have invented a new, original, and ornamental
Design for a Weighing Scale, of which the follow-
ing is a specification, reference being had to the
accompanying drawing, forming a part thereof.

Fig. 1 is a top plan view of a weighing scale em-
bodying my new design.

Fig. 2 is a side elevational view thereof.

Fig. 3 is a front elevational view of the same.

I claim:

The ornamental design for a weighing scale, as
shown.

JOHN R. MORGAN.
